CLAIM

The ornamental design for a laser marking machine, as shown and described.

DESCRIPTION

FIG. 1 is a top, rear and left side perspective view of a laser marking machine showing my new design;

FIG. 2 is a bottom, front and right side perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1; and,

FIG. 11 is an enlarged view of portion 11 in FIG. 2.

The broken lines in the drawings illustrate portions of the laser marking machine which form no part of the claimed design.

The oblique shade lines in the drawings represent a transparent surface.
